SOLE PRESSING MACHINE

Charles Turner Jones, Leicester, England, assignor to United Shoe Machinery Corporation, Paterson, N. J., a corporation of New Jersey

Application September 8, 1932, Serial No. 632,152
In Great Britain September 23, 1931

22 Claims. (Cl. 192—133)

This invention relates to sole pressing machines and is illustrated herein as embodied in a machine of the type disclosed in Letters Patent of the United States No. 861,746, granted July 5, 1907, upon an application of B. F. Mayo.

Machines of the type illustrated in the above-mentioned Letters Patent are provided with twin sole pressing mechanisms each comprising a shoe supporting member and a cooperating sole pressing member mounted for swinging movements relatively to each other, and with treadle controlled power operated means for operating the twin mechanisms alternately, one shoe support and pressing member remaining at rest at the 15 front of the machine in a work receiving position while the other support and pressing member are swung rearwardly to apply pressure progressively to the sole of a shoe.

In the operation of the machine a shoe is 20 moved from and another shoe placed on the stationary support before the treadle is depressed by the operator to connect that support and pressing member to their operating means. In mounting a shoe on or removing it from the stationary support it is the usual practice for the operator to extend one or both of his arms somewhat across the machine. If the shoe upper is of comparatively stiff and heavy material considerable effort is required to force the heel end of the upper 25 down on the heel end of the support and in this effort the operator may slip and fall more or less forwardly upon the machine. In that event there is danger of injury to the operator by having that arm which is close to the moving support and 30 pressing member crushed between that support and member as they swing relatively to each other to apply pressure to the sole of a shoe. Furthermore, any accidental depression of the treadle for connecting the stationary support and 35 pressing member to their operating means may result in one or both of the operator's arms or hands being caught between that support and pressing member as they are swung rearwardly. It is, therefore an object of the present invention 40 to provide in such a machine means for preventing the arm or hand of an operator from being caught between the shoe supporting member and the sole pressing member as these members are moved relatively to each other to apply pressure 45 to the sole of a shoe.

According to a feature of the invention, novel means is provided which is movable in a direction opposite to the direction of movement of the shoe support and pressing member to prevent the 50 arm or hand of an operator from being caught

between these parts during the sole pressing operation. As shown herein, this means comprises a pair of bars which extend upwardly, one on each side of the support and the pressing member, a considerable distance above the upper surface of the support. Preferably and as illustrated, the bars are mounted for swinging movement about the same fulcrum as the support and means is provided which is controlled by the swinging of the sole pressing member about its fulcrum for swinging the bars about their fulcrum in a direction opposite to that of the movement of the support and pressing member. In accordance with a further feature of the invention the construction is such as to accelerate the movement of the bars past the support and pressing member to insure the removal of the operator's arm or hand from between these parts before they have been moved into position to apply pressure to the sole. In accordance with another feature there is provided means arranged to lessen the force of the action of the bars on the arm or hand of the operator, this means, as illustrated, comprises a yielding device between the bars and their operating means arranged to permit the bars to yield to a limited extent as they engage the arm or hand of the operator before the bars are moved positively forward to remove the operator's arm or hand from between the shoe support and the sole pressing member.

A further feature of the invention consists in novel means that may be utilized, as an alternative, for stopping the operation of the machine if the arm or hand of an operator is in position to be caught between the shoe support and the sole pressing member as they are moved to apply pressure to the sole, the construction shown comprising a two-part lever for supporting the above-mentioned bars, the parts of the lever being mounted for relative swinging movement to connect the bars and their operating means to means for stopping the operation of the machine when the forward movement of the bars is obstructed by the arm or hand of an operator.

The above and other features of the invention including various novel details of construction and combinations of parts will now be more particularly set forth by reference to the accompanying drawings and will be pointed out in the claims.

In the drawings,

Fig. 1 is a view in side elevation of as much of a machine of the type illustrated in the above-mentioned Letters Patent as it is necessary to refer to for an understanding of the present invention.

tion, with novel features of the invention embodied therein;

Fig. 2 is a view in front elevation of the right-hand portion of the machine shown in Fig. 1;

5 Fig. 3 is a detail view partly in cross-section of a device for permitting limited relative yielding movement between the bars and their operating means when the forward movement of the bars is obstructed by the arm or hand of an 10 operator;

Fig. 4 is a view in side elevation illustrating a modified construction for connecting the operating means for the bars to mechanism for stopping the operation of the machine, and

15 Fig. 5 is a view in front elevation of the parts shown in Fig. 4.

The machine herein shown, like the machine of the Letters Patent mentioned, is provided with 20 duplicate sets of shoe supports and pressing members, each set comprising a last carrier or jack and a cooperating sole pressing form, each set being operated independently of the other to apply leveling pressure progressively to the sole 25 of a shoe. The jacks and forms are mounted to operate as in the machine of said Letters Patent with the exception that the axis about which the forms oscillate is located to the rear of the axis about which the jacks oscillate, instead of being located in the same vertical plane with said axis. 30 Only one set of jacks and forms is shown in detail or need be referred to for an understanding of the present invention.

As shown in Figs. 1 and 2 each jack 10 is 35 pivotally mounted upon a transversely extending shaft 12 mounted in suitable bearings carried by the frame 14 of the machine. Each jack is connected by a link 16 to a carrier 17 for a sole-pressing form 18 which carrier is pivoted at 20 to the frame 14. The jacks are connected by 40 links 22 to treadle-controlled power-operated means in the same manner as in the machine of the Letters Patent above referred to. The means for imparting operative movement to each jack and form is not shown herein but is fully illustrated and described in said Letters Patent. It 45 will be understood that a shoe is mounted on a last 21 on the jack 10 by the operator when the jack is in its outermost position and that, in the 50 operation of the machine, the jack and its cooperating sole-pressing form are swung inwardly or rearwardly away from the operator to apply 55 rolling pressure to the sole, after which the jack and form are brought to rest with the jack in its outermost position to permit a shoe to be removed from the jack and another shoe placed thereon.

Threaded into the outer end of the shaft 12 and concentric with the axis thereof is a shouldered stud 24 upon which is pivotally mounted a bracket 26 provided with a forked upper end to the arms 28 of which there are secured rods or bars 30 which extend upwardly, one on each side of and close to the jack 10. Means are provided which will presently be described for swinging the bracket 26 and the bars 30 forwardly as the jack and its cooperating form are swung rearwardly to apply pressure progressively to the sole of a shoe mounted on the jack. As shown, the bars 30 extend upwardly a considerable distance above the upper surface of the last 21 so that in their forward swinging movement they engage and push forwardly the hand or arm of the operator if it is in such a position that it would be caught between the bottom of the shoe on the jack 10 and the form 18 as the jack and form come together during their rearward swinging

movement. Preferably the forward movement of the bars 30 is accelerated in order to insure removal of the operator's arm or hand from between the jack and form before the jack and form are moved rearwardly into position to apply pressure to the sole as will be hereinafter described.

Pivotedly connected at 32 to the bracket 26 is a rod 34, the upper end of which is pivotally connected to one arm 36 of a bell-crank lever 38 pivoted at 40 to a bracket 42 secured to the frame 14 of the machine. The bell-crank lever 38 is provided with an upwardly and rearwardly extending arm 44 the upper surface of which is formed as a cam 46. The lever 38 is urged in a counter-clockwise direction as viewed in Fig. 1 by 90 a spring 48, one end of which is connected to the arm 36 and the other end of which is connected to the frame 14. Movement of the lever 38 under the influence of the spring 48 is limited by engagement of the cam 46 with a roll 50 which is carried by the pivoted sole-pressing form carrier 17, the construction being such that as the sole-pressing form 18 is swung downwardly and rearwardly from its fully forward position, the bell-crank lever 38 is swung in a clockwise direction 100 as viewed in Fig. 1 and through the rod 34 and bracket 26, the bars 30 are swung in a counter-clockwise direction from a position rearwardly of the jack 10 forwardly toward the operator. The lever 38 is partially enclosed by a cover 52 secured to the frame 14, the upper portion of which is cut away to permit the roll 50 to engage the cam 46. The configuration of the cam 46 is such that the forwardly swinging bars 30 are moved at a greater rate of speed than the rearwardly 110 swinging jack and form so that the bars 30 will be forward of the "bite" where the shoe bottom and form meet before the shoe bottom and form engage each other. Thus any part of the operator's arms or hands which may be in position 115 to be injured by being caught between the shoe bottom and the form will be forcibly removed by the forwardly swinging bars 30 before the sole pressing form 18 engages the shoe bottom. The upper ends of the bars 30 are bent forwardly as 120 shown so that if the sleeve of the operator's coat, for example, catches on one of the bars, the bar, as it swings rearwardly, will release the sleeve and not drag it and the operator's arm back into the machine. As shown particularly in Figs. 1 125 and 2 there is secured to the bracket 26 a thin plate 53 which acts to prevent any part of the operator or his clothing from being caught between the forwardly swinging bracket 26 and the frame 14 of the machine.

The outside bars of each pair and the inner bar of the right-hand pair are substantially straight except at their upper ends as above described, while the inner bar of the left-hand pair only is bent somewhat rearwardly from its lower end and 135 then forwardly, as shown in Fig. 1, so as to provide more clearance for the left arm of the operator while he is removing a shoe from or placing a shoe on the right-hand last. In placing a shoe on a last, the operator usually positions the toe end of the shoe on the last with his right hand and then forces the heel end of the shoe down on the last by placing his left hand around the heel end and partly on the tread surface of the shoe. In mounting a shoe on the right-hand jack, the operator's left arm naturally comes close to the swinging jack and form on the left and, accordingly, the inner bar of the left-hand pair is shaped as above described so as not to interfere unduly with the operation of placing a 140 145 150

- shoe on the right-hand last. The shape of this bar, though bent, is such that it will prevent the operator's left arm from being caught between the left-hand last and form. 80
- 5 For permitting the bars 30 to yield to a limited extent in their forward movement after they engage the arm or hand of the operator there may be provided a yielding device for connecting the bars 30 and their operating means. 85
- 10 As shown in Fig. 3, instead of the rod 34 there may be provided a rod formed in two parts connected by a sleeve 54 which is secured to the lower portion 56 of the rod and is provided with a pin 58 which extends through a lengthwise slot 60 formed in the lower end of the upper portion 62 of the rod. Between the ends of the lower and upper portions of the rod there is mounted in the sleeve a spring 64 which is arranged to yield when the forward movement of the bars 30 is obstructed 90
- 15 and this yielding movement is limited by engagement of a collar 66 secured to the upper portion 62 with the upper end of the sleeve 54. The slot 60 is of sufficient length to permit the spring 64 to yield until the collar 66 engages the upper end 95
- 20 of the sleeve 54 after which the bars 30 are moved positively forward to remove the arm or hand of the operator from between the jack and form. 100
- 25 The illustrated machine like the machine of the Letters Patent previously mentioned is provided with mechanism under the control of the operator for disconnecting the jack and form from their operating means at any point in their cycle of operation. This mechanism which is not shown or described herein in detail since it 105
- 30 is fully shown and described in the Letters Patent hereinbefore mentioned, is controlled by a pull rod 68 (Fig. 4) which extends forwardly into a convenient position to be grasped by the hand of an operator and forward movement of which 110
- 35 is operative to throw the operating mechanism of whichever jack and form are being operated out of operation. 115
- 40 The illustrated machine may be provided with means for connecting the operating means for 120
- 45 the bars 30 to the pull rod 68 to stop the operation of the machine when the forward movement of the bars 30 is obstructed by the arm or hand of an operator. As shown in Figs. 4 and 5 there is provided a two-part lever 70, the parts 125
- 50 of which are mounted for relative swinging movement, for supporting the bars 30. The lower portion 72 of the two-part lever is pivotally mounted on the shouldered stud 24 and has pivotally connected to it at 74 an upper portion 76 130
- 55 to which the bars 30 are secured and which is normally held against a stop 78 formed on the lower portion 72 by means of a spring 80. The lower portion 72 has pivotally connected to it a rod 34 which is preferably a solid rod as shown 135
- 60 in Fig. 1. The upper portion 76 of the two-part lever is provided with a downwardly extending arm 82 provided with ratchet teeth 84 which are arranged to engage, upon relative movement of the upper and lower portions of the two-part lever 70, ratchet teeth 86 formed on a segment lever 88 which is pivotally mounted on the shaft 140
- 65 12 and is connected to the pull rod 68 by a link 90. From the above description it will be seen that as the bars 30 in their forward movement 145
- 70 are obstructed by the arm or hand of the operator relative movement between the upper and lower portions of the two-part lever 70 is permitted, by reason of the yielding of the spring 30, until the ratchet teeth 84 engage the ratchet teeth 86 formed on the lever 88, after which as 150
- the two-part lever is moved forwardly the pull rod 68 is also moved forwardly to stop the operation of the machine. It will be seen also that any forward movement of the bars 30 after the ratchet teeth have become engaged and before the machine is stopped is in a direction to move the arm or hand of the operator, which is in the path of the forward movement of the bars, away from the jack and form. Removal of the arm or hand of the operator permits the spring 80 to disengage the ratchet teeth 84, 86 after which the machine resumes its operation. The mechanism above described for connecting the bars 30 to the pull rod 68 is substantially the same for each jack and form, there being two rearwardly extending links 90 connected to the pull rod 68.
- Having thus described my invention, what I claim as new and desire to secure by Letters Patent of the United States is:
1. In a sole-pressing machine, the combination with a shoe support and a cooperating sole-pressing member, said support and member being both movable simultaneously in one direction while also moving relatively to each other to apply pressure to the sole of a shoe on the support, of means movable in a direction opposite to that of the movement of the support and pressing member to prevent the arm or hand of an operator from being caught between the support and the pressing member during the sole-pressing operation. 105
2. In a sole-pressing machine, the combination with a shoe support and a cooperating sole-pressing member, said support and member being movable in one direction while also moving relatively to each other to apply pressure to the sole of a shoe on the support, of means movable in a direction opposite to that of the movement of the support and pressing member to insure removal of the arm or hand of an operator from between the support and the pressing member before the support and the pressing member by their continued movements arrive in position to apply pressure to the sole. 110
3. A sole-pressing machine having a shoe support and a sole-pressing member, said support and member being mounted for movement in one direction to apply pressure progressively to the sole of a shoe on the support, and means movable in a direction opposite to that of the movement of the support and pressing member for forcibly removing the arm or hand of an operator from between the support and the pressing member if the operator's arm or hand is in position to be caught between the pressing member and the bottom of a shoe on the support. 115
4. A sole-pressing machine having a shoe support and a sole-pressing member, said support and member being mounted for swinging movement relatively to each other to apply pressure progressively to the sole of a shoe on the support, and means movable relatively to the support and pressing member and arranged forcibly to remove the arm or hand of an operator from between the support and the pressing member before the support and pressing member have been moved into position to apply pressure to the sole. 120
5. In a sole-pressing machine, the combination with a shoe supporting jack and a cooperating sole-pressing form mounted for swinging movement in one direction to apply pressure to the sole of a shoe on the jack, of means comprising a pair of bars, one on each side of the jack and form, movable in a direction opposite to that of the movement of the jack and form for forcibly removing the arm or hand of an operator which 125

may be in such a position that during said swinging movement of the jack and form it would be caught between the form and the bottom of the shoe on the jack.

5 6. In a sole-pressing machine, the combination with a shoe-supporting jack and a cooperating sole-pressing form, said jack and form being mounted for relative swinging movement to apply pressure to the sole of a shoe on the jack, of a 10 member mounted for swinging movement about the same fulcrum as the jack, and means for swinging said member past the jack and form in a direction to remove the arm or hand of an operator from between said jack and form.

15 7. In a sole-pressing machine, the combination with a shoe-supporting jack, a cooperating sole-pressing form, and means to swing the jack and form in one direction to apply pressure progressively to the sole of a shoe on the jack, of a 20 bar extending upwardly above the upper surface of the jack, and means for swinging the bar past the jack and form in a direction opposite to that of the movement of the jack and form.

3. In a sole-pressing machine, the combination 25 with a pivoted shoe-supporting jack, a pivoted sole-pressing form, and means for swinging said jack and form about their pivots to apply pressure progressively to the sole of a shoe on the jack, of a pair of bars one on each side of the jack and form, a support for said bars mounted for swinging movement about the same pivot as said jack, and means for swinging said support about its pivot to move said bars past the jack and form.

35 9. In a sole-pressing machine, the combination with a shoe-supporting jack, a sole-pressing form, said jack and form being mounted for relative swinging movements, and means for swinging said jack and form about their fulcrums to apply pressure to the sole of a shoe on the jack, of a member 40 mounted for swinging movement and arranged to engage and remove the arm or hand of an operator from between said jack and form, and means for swinging said member about its fulcrum, said last-named means being arranged to accelerate the movement of the member to insure removal 45 of the arm or hand of an operator before the jack and form have been moved into position to apply pressure to the sole.

10. In a sole-pressing machine, the combination 50 with a pivoted shoe-supporting jack, a pivoted sole-pressing form, and means for swinging said jack and form about their pivots to apply pressure progressively to the sole of a shoe on the jack, of a pair of bars one on each side of the jack and form, a support for said bars mounted for swinging movement about the same pivot as said jack, and means for swinging said support about its pivot to move said bars in a direction to remove the arm or hand of an operator from between the 55 jack and form, said means being arranged to accelerate the movement of the bars to insure removal of the operator's arm or hand before the jack and form have been moved into position to apply pressure to the sole.

65 11. In a sole-pressing machine, the combination 60 with a shoe-supporting jack and a form carrier mounted for swinging movements to apply pressure to the sole of a shoe on the jack, of means operated by the swinging form carrier for forcibly removing the arm or hand of an operator from between the jack and form if the operator's arm or hand is in position to be caught between the 70 form and the bottom of the shoe on the jack.

75 12. In a sole-pressing machine, a shoe-supporting jack, a sole-pressing form, said jack and form

being mounted for swinging movements, means for swinging the jack and form about their fulcrums to apply pressure to the sole of a shoe on the jack, a lever mounted for swinging movement about the same fulcrum as the jack, a pair of bars carried by said lever, said bars extending upwardly one on each side of the jack and form, and means operated by the swinging of the form about its fulcrum for swinging said lever about its fulcrum to move said bars past the jack and form in a direction opposite to that of the movement of the jack and form. 80

13. In a sole-pressing machine, the combination with a shoe-supporting jack and a cooperating sole-pressing form, said jack and form being mounted for rearward swinging movements to apply pressure to the sole of a shoe on the jack, of a pair of bars one on each side of the jack and form, and means arranged during rearward swinging movement of the jack and form 90 to swing the bars forwardly at a greater rate of speed than that of the jack and form to remove the arm or hand of an operator from between the jack and form before the jack and form have been swung rearwardly into position to apply 95 pressure to the sole.

14. In a sole-pressing machine, the combination with a shoe-supporting jack and a cooperating sole-pressing form mounted for swinging movements in one direction to apply pressure to the 105 sole of a shoe on the jack, of means movable in a direction opposite to that of the movement of the jack and form and arranged yieldingly to engage and then forcibly to remove the arm or hand of an operator which may be in such a position 110 that during said swinging movement of the jack and form it would be caught between the form and the bottom of the shoe on the jack.

15. In a sole-pressing machine, the combination with a shoe-supporting jack and a cooperating sole-pressing form mounted for swinging movements in one direction to apply pressure to the sole of a shoe on the jack, of a pair of bars one on each side of the jack and form, and means including a yielding device for moving the bars 115 in a direction opposite to that of the movement of the jack and form to remove the arm or hand of an operator from between the jack and form, said means being arranged to permit the bars to yield to a limited extent as they engage the 120 arm or hand of an operator.

16. A sole-pressing machine having a shoe-supporting member and a sole-pressing member, said members being mounted for movement in one direction to apply pressure progressively to 130 the sole of a shoe on the supporting member, manually controlled means to stop the operation of the machine, and means arranged to move in a direction opposite to that of the movement of said members and, by engagement with the arm 135 or hand of an operator that may be in position to be caught between said members, to operate the manually controlled means to stop the operation of the machine.

17. A sole-pressing machine having, in combination, a shoe-supporting jack, a sole-pressing form, operating means therefor arranged to move the jack and form in one direction to apply pressure to the sole of a shoe on the jack, manually controlled means to stop the operation of the 145 machine, a pair of bars one on each side of the jack and form, means for moving the bars in a direction opposite to that of the movement of the jack and form, and mechanism controlled by said last-named means for operating the manually 150

- controlled means to stop the operation of the machine upon engagement of one of the bars with the arm or hand of the operator.
18. A sole-pressing machine having, in combination, a shoe-supporting jack, a sole-pressing form, said jack and form being mounted for relative swinging movements to apply pressure to the sole of a shoe on the jack, operator-controlled means to stop the operation of the machine, a member movable relatively to the jack and form and arranged to engage the arm or hand of an operator that may be in position to be caught between said jack and form, and means for connecting said member to the operator-controlled means to stop the operation of the machine upon engagement of said member with the arm or hand of the operator. 40 80
19. A sole-pressing machine having, in combination, a shoe-supporting jack, a sole-pressing form, means for moving the jack and form in a direction to apply pressure to the sole of a shoe on the jack, operator-controlled means for stopping the operation of the machine, a bar, means for moving the bar past the jack and form, and mechanism for connecting the last-named means to the operator-controlled means to stop the operation of the machine upon engagement of the bar with the arm or hand of an operator. 45 85
20. A sole-pressing machine having, in combination, a shoe-supporting jack, a sole-pressing form, means for moving the jack and form in one direction to apply pressure to the sole of a shoe on the jack, operator-controlled means to stop the operation of the machine, a pair of bars one on each side of the jack and form, means for moving the bars past the jack and form in an opposite direction, and mechanism for connecting the last-named means to the op- 90 95
21. A sole-pressing machine having, in combination, a shoe-supporting jack, a sole-pressing form, operating means therefor arranged to move the jack and form in one direction to apply pressure to the sole of a shoe on the jack, means under the control of the operator for stopping the operation of the machine, a pair of bars, and means for moving the bars past the jack and form in an opposite direction, said last-named means including a two-part lever the parts of which are mounted for relative swinging movement to connect with the operator-controlled means to stop the operation of the machine upon engagement of one of the bars with the arm or hand of the operator. 100 105
22. A sole-pressing machine having, in combination, a shoe-supporting jack, a sole-pressing form, operating means therefor arranged to move the jack and form in one direction to apply pressure progressively to the sole of a shoe on the jack, means under the control of the operator for disconnecting the jack and form from their operating means, a pair of bars one on each side of the jack and form, means for moving the bars past the jack and form in an opposite direction including a two-part lever the parts of which are mounted for relative swinging movement to connect with the operator-controlled means upon the engagement of one of the bars with the arm or hand of the operator, and a spring connecting the two parts of the lever and against the resistance of which the parts are thus relatively movable. 110 115
